UNITED STATES PATENT OFFICE

100,252

DESIGN FOR A SHOE

Jacob Abowitz, New York, N. Y.

Application May 27, 1936, Serial No. 62,862

Term of patent 3½ years

To all whom it may concern:

Be it known that I, Jacob Abowitz, a citizen of the United States and resident of New York city, in the county of New York and State of New York, have invented a new, original, and ornamental Design for a Shoe, of which the following is a specification, reference being had to the accompanying drawing, forming part thereof, in which,

Fig. 1 is a plan view of the shoe showing my new design;

Fig. 2 is a side view of the shoe shown in Fig. 1, and

Fig. 3 a plan view of the shoe shown in Fig. 1 with saddle taken off to show the goring in the throat of the vamp.

I claim:

The ornamental design for a shoe as shown and described.

Dated, May 25, 1936.

JACOB ABOWITZ.
